UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT.

SPECIFICATION forming part of Design No. 27,512, dated August 10, 1897.

Application filed December 26, 1896. Serial No. 617,115. Term of patent 7 years.

To all whom it may concern:

Be it known that I, FREDERICK W. CHESSON, a citizen of the United States, residing at Waterbury, in the county of New Haven and State 5 of Connecticut, have invented and produced a new and original Design for Metal Mounts, of which the following is a specification, reference being had to the accompanying drawings, in which—

- 10 Figure 1 is an elevation, and Fig. 2 is a plan, of my design.
The general configuration of the metal mount is round; and the leading features of my design consist in the cylindrical body having a group of parallel connected circumferential semicircular beads of equal width, the 15 adjacent conical portion, band, and cove, the

convex rib, and adjacent bands, and the contracted end.

The group of parallel connected circumferential semicircular beads of equal width are shown at *a*, the adjacent conical portions at *b b'*, the bands at *c c'*, the coves at *d d'*, the convex ribs at *e e'*, the bands at 2 and 3, and the contracted ends at *ff'*. 20 25

What I claim is—

The design for a metal mount, substantially as shown and described.

Signed by me this 17th day of December, A. D. 1896.

F. W. CHESSON.
